UNITED STATES PATENT OFFICE.

VIRGILIO SBIGOLI, OF CHICAGO, ILLINOIS.

DESIGN FOR AN AUTOMOBILE RADIATOR CAP.

Application filed September 8, 1922. Serial No. 3,652. Term of patent 14 years.

To all whom it may concern:

Be it known that I, VIRGILIO SBIGOLI, a subject of the King of Italy, residing at Chicago, in the county of Cook and State of Illinois, have invented a new, original, and ornamental Design for Automobile Radiator Caps, of which the following is a specification, reference being had to the ac-

companying drawing forming a part thereof, in which:—

Fig. 1, represents a front elevation and Fig. 2, a side elevation of my new design.

I claim:

The ornamental design for an automobile radiator cap, as shown.

VIRGILIO SBIGOLI.
